United States Patent Office

Des. 194,737
Patented Mar. 5, 1963

194,737

SIGN

Nelvin C. Zeitvogel, La Mesa, Calif., assignor to California Neon Products, San Diego, Calif., a corporation of California

Filed July 17, 1962, Ser. No. 70,960

Term of patent 3½ years

(Cl. D1—12)

FIG. 1

FIG. 2

FIG. 3

FIG. 4

FIG. 1 is a perspective view of a sign, showing my new design;

FIG. 2 is a side elevation view thereof;

FIG. 3 is a cross sectional view thereof taken on line 3-3 of FIG. 2, the base and lower sign holder being omitted for convenience of illustration; and

FIG. 4 is a cross sectional view thereof taken on line 4-4 of FIG. 2.

I claim:

The ornamental design for sign, as shown and described.
